JAMES J. B. McELRATH, OF CENTRE, ALABAMA, ASSIGNOR OF ONE-HALF TO
J. D. PICKLE, OF SAME PLACE.

DESIGN FOR A MATCH-BOX.

SPECIFICATION forming part of Design No. 32,571, dated April 24, 1900.

Application filed March 30, 1900. Serial No. 10,854. Term of patent 3½ years.

To all whom it may concern:

Be it known that I, JAMES J. B. McELRATH, a citizen of the United States, residing at Centre, in the county of Cherokee and State of Alabama, have invented and produced a new and original Design for a Match-Box, of which the following is a specification, reference being had to the accompanying drawing, forming a part thereof, which represents a front elevation of a match-box embodying the features of my design.

The leading feature of the design consists of a body having a contour approximating that of a shield surmounted by the representation of a partially-open tent disclosing a hand with a heart delineated thereon. The

tent is decorated with an ornamental canopy bearing an eye, and at the side of the tent crossed shepherds' crooks and crossed arrows appear. Below the tent the shield is decorated with the links of a chain. 20

The minor features of the design consist of pockets represented as upon the body of the shield.

I claim—

The design for the match-box herein shown and described.

JAMES J. B. McELRATH.
